(57) CLAIM

The ornamental design for a nursing cap as shown and described.

DESCRIPTION

The patent or application file contains a least one drawing/photograph executed in color. Copies of this patent or patent application publication with color drawing(s)/photograph(s) will be provided by the Office upon request and payment of the necessary fee.

FIG. 1 is a right side elevational view of a nursing cap showing an embodiment of my new design.

FIG. 2 is a perspective view thereof.

FIG. 3 is a cross-sectional view thereof along line 3-3 in FIG. 4.

FIG. 4 is a bottom plan view thereof.

FIG. 5 is a top plan view thereof.

FIG. 6 is a right side elevational view of a nursing cap showing another embodiment of my new design.

FIG. 7 is a top plan view thereof.

FIG. 8 is a perspective view thereof.

FIG. 9 is a cross-sectional view thereof along line 9-9 in FIG. 7.

FIG. 10 is a bottom plan view thereof.

FIG. 11 is a right side elevational view of a nursing cap showing another embodiment of my new design.

FIG. 12 is a bottom plan view thereof.

FIG. 13 is a cross-sectional view thereof along line 13-13 in FIG. 12.

FIG. 14 is a top plan view thereof.

FIG. 15 is a perspective view thereof.

FIG. 16 is a cross-sectional view along line 16-16 in FIG. 17 of a nursing cap showing another embodiment of my new design.

FIG. 17 is a bottom plan view thereof.

FIG. 18 is a perspective view thereof.

FIG. 19 is a top plan view thereof.

FIG. 20 is a right side elevational view thereof.

FIG. 21 is a perspective view of a nursing cap showing another embodiment of my new design.

FIG. 22 is a right side elevational view thereof.

FIG. 23 is a top plan view thereof.

FIG. 24 is a bottom plan view thereof.

FIG. 25 is a cross-sectional view thereof along line 25-25 in FIG. 24.

FIG. 26 is a top plan view of a nursing cap showing another embodiment of my new design.

FIG. 27 is a right side elevational view thereof.

FIG. 28 is a bottom plan view thereof.

FIG. 29 a cross-sectional view thereof along line 29-29 in FIG. 28; and,

FIG. 30 is a perspective view thereof.

1 Claim, 30 Drawing Sheets
